SCUPPER PLUG

Ernest Alexander Brooks, Baltimore, Md.

Application August 24, 1939, Serial No. 291,669

3 Claims. (Cl. 114—0.5)

Heretofore, it has been the practice to fill scupper holes of vessels carrying oil with wooden plugs and this invention has for its object to provide an improved plug for this purpose.

5 In accomplishing this object, I have provided the improved details of construction the preferred form of which is illustrated in the accompanying drawing, wherein—

Figure 1 is a plan view of the plug device.

10 Figure 2 is an end view thereof.

Figure 3 is a plan view of a fragment of a ship showing a scupper hole and plug clamping means.

Figure 4 is a view in side elevation of the structure of Figure 3.

15 Figure 5 is a view along section 5—5 of Figure 3.

The plug device consists of a plug element or body 1 and a face plate 1'. The plug body is made up of a metallic core, preferably of steel 20 about $\frac{1}{4}$ " thick and a covering of lead. The lead is cast on the core completely covering the same, thereby giving the core added strength. The layer of lead should be about $\frac{1}{2}$ inch thick. The plug body is tapered in the manner shown in

25 Figures 1 and 2 to facilitate inserting it in place. The face plate 1' is attached to the broader or rear end of the plug and extends about equal distances on each side thereof. A notch or re-

cess 3 is formed in the plate at each side of the 30 plug for convenient engagement with clamps so that it may be conveniently clamped in the scupper hole. The face plate is further provided with a ring 2 whereby a chain may be attached to the plug, the other end of the chain may be

35 attached to the shackle 6, Figure 4.

Clamping means, 4, 4', illustrated in Figures 3, 4 and 5 may be provided and in such case they should be attached to the side of the vessel adjacent the scupper hole 1 which it is desired to close. The clamping means include rods 4, preferably made of brass, pivotally attached to the vessel, one at each side of the hole and clamp units 4', one on each rod. Nuts are threaded on the rods to draw the clamp units 4' into the notches in the face plate and thereby draw the 10 plug into the hole. Support elements 5 are positioned adjacent the pivots of rods 4 so that the rods may rest therein when not in use.

Having described the invention, what I claim to be new is:

1. A plug device for closing a scupper hole aboardship comprising a plug body of a size to close the hole, said body including a metallic core and a unitary lead casing integrally attached thereto and completely covering the same, 20 a plate member secured at its mid-portion to one end of said body and extending beyond opposite sides thereof to provide arms, each of which are provided with a recess to receive clamping means whereby the plug may be held in the hole. 25

2. A scupper plug as claimed in claim 1 wherein the plug body is tapered from the larger end at the plate member to the front end.

3. A scupper plug as claimed in claim 1 and including clamping means adapted to be secured 30 to the side of the ship and cooperate with said recesses in the arms in the plate member whereby the plug may be securely held in the scupper hole.
